UNITED STATES PATENT OFFICE.

WILLIAM T. CROSS, OF KEWANEE, ILLINOIS.

DESIGN FOR A MONUMENT.

Specification forming part of Design No. 6,368, dated January 28, 1873.

To all whom it may concern:

Be it known that I, WILLIAM T. CROSS, of Kewanee, in the county of Henry and State of Illinois, have invented a Design for Marble Monument, of which the following is a specification:

This is a design for a child's monument, which has four equal sides, the front side being the one shown in the drawing, to which reference is made.

A represents a cut limestone base; B, a molded marble base; C, an ornamental carved ogee die; and D, an urn with a flower in the neck of it. The flower in the neck of the urn I use as an ornament. F, a scroll carved on one side of the sloping top of the die, containing the motto, "One sweet flower has drooped and faded;" G G, ornamental leaves carved upon each of the four corners of the monumental die, the scroll-work of the bottom of the leaves being continued along the bottom of the die till it meets in the center,

and is intertwined in the manner represented at H.

I am aware that an ogee die is not new, and do not claim it.

What I specially claim as my invention is—

1. A design for a child's monument having an ogee die ornamented in the manner described, with scroll-leaf work intertwining below, and scroll, with motto as aforesaid, on the top of the die near the base of the urn, as set forth.

2. The flower in the neck of the urn, in combination with the scroll and motto below, as described.

3. The combination and proportion of the architectural and ornamental parts, as set forth.

December 5, 1872.

WM. T. CROSS.
